Samuel G. Hurlbut

UNITED STATES PATENT OFFICE.

SAMUEL G. HURLBUT, OF ELYRIA, OHIO.

FARM-GATE.

SPECIFICATION forming part of Letters Patent No. 224,915, dated February 24, 1880.

Application filed July 30, 1879.

To all whom it may concern:

Be it known that I, SAMUEL G. HURLBUT, of Elyria, in the county of Lorain and State of Ohio, have invented certain new and useful Improvements in Farm-Gates; and I do hereby declare that the following is a full and exact description thereof, reference being had to the accompanying drawings, and to the letters of reference marked thereon, in which like letters refer to like parts in the different figures.

To enable others skilled in the arts to make and use my invention, I will proceed to describe its construction and operation.

15 In the drawings, Figure 1 is a horizontal section, Fig. 2 is a plan view, Fig. 3 is a side elevation, Fig. 4 is a vertical section, and Fig. 5 is a side elevation, of gate.

The nature of my invention consists in the 20 construction and operation of that class of farm-gates which are opened by sliding backward in the direction of the fence a portion or the whole of their length upon a pivoted roller, and then swinging said gate around to a position at right angles to the line of its former 25 position.

My invention relates more particularly to the construction and operation of a hinged roller on which said gate slides.

30 In the drawings, A represents a bar, which is constructed in the form seen in Figs. 1, 2, 3, and 4, having through its center a hole, which serves as a bearing, and receives a journal, c, of wheel B. Said bar A is, at its extremities, provided with journals d d', which are sunk below the surface of the bar, so as to form shoulders e e' f f'. In practice they are cut in a concave form, so as to fit a round rod, such as eyebolts are usually made of.

40 g g' represent two eyebolts, which are secured to the post in the usual manner, and extend around the journals d d' and engage them in such a manner as to form bearings, in which they work freely, while at the same time each 45 eyebolt serves as a support for said bar, the shoulders e and f of said bar both resting upon their respective eyebolts, thus being sustained in a vertical position by their mutual strength.

B represents a wheel, which is constructed 50 in the form seen in the drawings, Figs. 1, 2, 3, and 4, in which c represents a journal, which

is formed in the center of said wheel within an annular recess. Said journal is so positioned as to bring its bearing-point, when in operation, within the thickness of the wheel, 55 in order to bring it as nearly as practicable under the center of gravity. Said recess is formed by flange i, which said flange forms the rim of said wheel. Said flange i is webbed to the journal c, as seen at j, Fig. 1. Upon the 60 outer surface of said flange i, and at its extreme edges, are formed other flanges, K K', which are designed for the purpose of engaging and holding the bars of the gate, as seen in Fig. 5.

The gate is constructed in the form seen in Fig. 5, having its bars arranged and secured in position in the usual manner employed in the construction of such gates. At the center of said gate a vertical cross-bar, l, is secured 70 to the horizontal bars, and is at that point, between the bars that engage the wheel, recessed out, as seen at m, so as to admit the free passage of the wheel, in order that the gate may be forced back to any desired distance beyond 75 its center.

The operation of my gate is as follows: The bar A is placed in position in the bearings of the eyebolts, by which it is held and supported in a vertical position in such a manner that 80 the weight is supported by the combined strength of both eyebolts. The journal c is inserted and secured in the bearing, so that it can revolve freely. The vertical center of bar A coincides nearly in the center of gravity by 85 reason of its being within the thickness of the wheel. The gate is then placed in position, as seen in Fig. 5, and may be forced either backward or forward, as desired, or turned from a right line to an angle of forty-five degrees, or, 90 if desired, to an angle of ninety degrees, more or less, at the will of the operator.

The gate may, when partially or fully opened, have its ends supported on a hook or otherwise, as seen at n, Fig. 5.

I am aware that a patent has been granted to J. B. Bolinger for an improvement in farm-gates, wherein he claims the wheel with a journal and its two integral arms in combination, when constructed, as described in his specification, with two eyebolts; but I am not aware that a gate wheel and hinge has been con-

structed having a straight bar, A, a central bearing, c, placed as described, and having shouldered bearings at its ends, as seen at $e\ e'$ $f\ f'$, for the purpose of suspending the weight 5 equally upon two eyebolts, as described.

I claim—

The oscillating vertical bar A, provided with a central bearing, and with shoulders $e\ e'$ $f\ f'$ near its extremities, forming recesses $d\ d'$, 10 in combination with the eyebolts $g\ g'$, and with

the wheel B, having projecting journal c, which latter enters the central bearing, and thus allows the bar or bearing to stand within the flanged rim or annular recess of the wheel, substantially as herein shown and described. 15

SAMUEL G. HURLBUT. [L. S.]
